UNITED STATES PATENT OFFICE.

IVY G. MAYWALD, OF TUCUMCARI, NEW MEXICO.

DESIGN FOR A GAME-BOARD.

50,074.

Specification for Design.

Patented Dec. 19, 1916.

Application filed October 27, 1916. Serial No.128,139. Term of patent 14 years.

To all whom it may concern:

Be it known that I, Ivy G. MAYWALD, a citizen of the United States, residing at Tucumcari, in the county of Quay and State of new Mexico, have invented a new, original, and ornamental Design for Game-Boards, of which the following is a specification, reference being had to the accompanying drawing, forming part thereof.

The figure is a plan view of a game board, showing my new design.

I claim:

The ornamental design for a game board, as shown.

IVY G. MAYWALD.

Witnesses:

J. J. HARRISON,
W. R. STECKMAN.
